EDMOND H. REYNIER, OF PASSAIC, NEW JERSEY.

TENTERING MACHINE.

Application filed June 11, 1928. Serial No. 284,505.

In tentering apparatus of the class in which there are two side-by-side elongated structures having longitudinal ways and tentering chains respectively movable on said structures and comprising fabric gripping clips arranged to be guided and held apart by the ways and adapted to undergo closing movement on each approach thereof to said ways so as to grip the fabric while traveling along the ways and to undergo opening movement on each departure thereof from said ways so as to release the fabric, it is practically impossible in the case of certain fabrics and in a single pass of the goods through a single tentering machine to avoid one or more of the clips failing to grip the fabrics, a consequence of which is of course that the fabric fails to be stretched or tentered in the transverse zone occupied by the failing clips; wherefore it has always been necessary to pass such fabrics two or more times through the machine or (which is the usual practice) to employ two or more machines and run the goods through the machines one after the other. My invention contemplates an improvement in tentering machines of this class whereby on a single pass through a single machine if a "miss" of the kind indicated occurs the goods will nevertheless be regripped and subjected to stretching by the failing clip or clips and there will be no portion of the fabric failing to be stretched.

In the drawing,

- Fig. 1 is a plan of the improved machine; Fig. 2 is a side elevation thereof; Fig. 3 a fragmentary plan on a large scale of a part of the machine embodying the invention; Fig. 4 a side elevation of what is shown in Fig. 3, with the clips removed; and Fig. 5 a section on approximately line 5—5, Fig. 3.

The mentioned side-by-side elongated structures or rails are indicated at 1 and they have grooves to form the mentioned ways 2, each of these grooves being here continuous, as usual, so that the portion 3 thereof forms a return for the portion or way 2 thereof. The left-hand end of the machine in Fig. 1 will be taken as the entering end of the machine and from such ends of the two structures the ways 2 diverge, as usual, so that the clips traveling along the same

duce the stretching or tentering of the goods.

The clips to form the two endless tentering chains, being linked together as indicated at 4 in Fig. 3, may be of any well-known type, that shown in the drawings being only an example. In such clip 5 is a fork-like body having a fixed lower apertured jaw 6 formed by one of its fork arms and a pivoted movable jaw 7 which coacts with the jaw 6 to grip the fabric and has an arm 8 operatively connected with a feeler lever 9 whose free end is positioned over the aperture in the fork arm 6: in the usual way, arm 7 having been by suitable means (which engages its extension 7^a) moved to open position, the fabric edge enters between 6—7, whereupon, arm 7 having been released, the feeler lever 9 is allowed to fall upon the goods which through the medium of lever 9 retains arm 7 elevated out of gripping relation until the edge of the fabric frees the feeler lever, which then falls into the recess and allows arm 7 to coact with arm 6 to grip the fabric. The opening movement of the arms 7 may be accomplished by the means 10, 11 at the opposite ends of each rail, being in this example wheels journaled in the rail on vertical axes. The wheels 10 effect the opening movement to release the fabric at the discharge end of the machine and instead of keeping the clips open until they again approach the ways 2 at the entering end of the machine, which would entail added parts and undue wear of the clips, I follow the usual practice and allow the clips to close by gravity on their progress along the return 3 and provide for their re-opening by the wheels 11 as they approach the ways 2 at the entering end of the machine and consequently the fabric.

As indicated, at the outset of or later during their progress along the ways (usually the former) some of the clips in the case of certain goods will fail to receive and hold the fabric edge, and in the thus-affected zone of the fabric there will be no stretching or tentering thereof. To remedy this defect I provide the ways 2 with bends 2^a each of which reaches toward the opposite way, and means 12 to control the movements of the jaws 7 at the bends. The bends are preferably placed at some points passed by the clips after they leave the mentioned diverging portions of the ways, as near said

portions so that if a failure occurs it may be corrected early in the progress of the failing clips along the ways; but they may be placed elsewhere in the ways, and there 5 may be more than one for each rail.

All the clips of course follow the bends 2^a in the ways and all are subject to the action of the controlling means 12 whether or not they fail to receive and hold the fabric

16 A. If they do not fail, the fabric edge remains therein, while the jaws 7 of the clips are withdrawn from their jaws 6, and so release the fabric, until the peaks of the bends are passed, whereupon the jaws 7 15 return into the gripping relation. If any clip fails, the movement of the defective clip toward the opposite way as it passes around the bend 2^a forces it against the stretched edge portion of the fabric (its jaw 7 being 20 already opened by the means 12), which thus enters the clip, ready to be gripped by said jaw as soon as the same is released by the means 12.

The means 12 functions with respect to 25 each clip jaw 7 substantially the same as each wheel 10—11, though it is in the example a fixed cam; that is to say, as the clip takes the bend 2^a in the way the extension 7^a of its jaw 7 encounters the cam and the 30 jaw is withdrawn, falling by gravity to gripping position as soon as the cam is passed.

Cam 12 is here provided with a fixed vertical bolt 13 which passes through a slot 35 14 in the rail arranged transversely of way 2, the bolt having a flattened key 13^a in the slot which prevents the cam from turning; the bolt has a clamping nut 15.

When the leading end of the goods is 40 introduced into the machine, if the cams 12 remained at that time active to open the clips, the goods would fail to be caught and carried along. Hence at this time the bolts 13 are released and the cams shifted to the 45 position lengthwise of slots 14 where they will fail to be engaged by the jaw extensions 7^a, whereby the leading end of the goods will remain held by the clips until it has passed the bends 2^a, upon which the cams

are returned to their normal or illustrated 50 positions.

Usually, both ways will be provided with the bends 2^a and means 12, though this is not indispensable.

Having thus fully described my invention, 55 what I claim is:

1. A tentering machine comprising two side-by-side elongated structures having longitudinal spaced ways, tentering clips arranged to be guided by said ways and each adapted to undergo closing movement on each approach thereof to the corresponding way so as to hold the fabric while travelling along such way and to undergo fabric-releasing movement on each departure thereof from said way, means to control such movements of the clips, one of said ways having, between the points at which said closing and releasing movements of the clips occur, a bend reaching toward the other way, and the clips guided by such ways being each adapted also to undergo fabric-releasing and closing movement at said bend, and means to control the latter releasing and closing movements of such 75 clips.

2. A tentering machine comprising two side-by-side elongated structures having longitudinal spaced ways, tentering clips arranged to be guided by said ways and each adapted to undergo closing movement on each approach thereof to the corresponding way so as to hold the fabric while travelling along such way and to undergo fabric-releasing movement on each departure thereof from said way, means to control such movements of the clips, one of said ways having, between the points at which said closing and releasing movements of the clips occur, a bend reaching toward the other way, and the clips guided by such way being each adapted also to undergo fabric-releasing and closing movement at said bend, and means to control the latter releasing and closing movements of such 90 clips shiftable transversely of the ways.

In testimony whereof I affix my signature.

EDMOND H. REYNIER.
